IRONING DEVICE

Edward Walker and Harry Crickler, Santa Ana,
Calif.; said Crickler assignor to said Walker

Application March 19, 1934, Serial No. 716,284

15 Claims. (Cl. 68—9)

Our invention relates to ironing devices and has particular reference to a device for ironing and folding rectangular sheets of material.

In laundry practice considerable difficulty is encountered in ironing and folding flat work, such as napkins, handkerchiefs, and the like, wherein it is desired to iron such articles and then fold the same at the center of the article. While no difficulty is encountered in ironing such flat articles, the folding of the same upon the proper center has required manual location of such centers by manual labor, and has required that the folding be done by hand, particularly when it was desired to handle a number of flat articles of different dimensions.

For example, in the laundering of table napkins a great many different sizes of napkins would be normally encountered during the laundering of any single batch which would require that the operator of any prior ironing machine, though readily ironing the work while flat, would be required to manually find the centers of the different sized napkins and to fold the same by a manual operation, seriously interfering with the rapidity with which such articles can be finished.

It is, therefore, an object of our invention to provide an ironing device which will automatically iron such flat pieces and automatically fold the same at their centers irrespective of the dimensions of the particular pieces worked upon.

Another object of our invention is to provide a device for automatically ironing and folding flat pieces in which the articles are fed into the machine by a device which automatically locates the center of the piece, irrespective of its dimensions.

Another object of our invention is to provide an ironing machine in which a plurality of different sized flat pieces may be fed into the machine, ironed therein, and each automatically folded upon its proper center.

Another object of our invention is to provide a machine of the character set forth in which an operator of the machine may successively feed flat pieces of varying sizes to the machine and in which the center of such pieces will be automatically located by the machine and the pieces be folded upon their respective centers and fed from the machine in a finished ironed and folded condition.

Another object of the invention is to provide an automatic center-locating device for flat pieces.

Another object of the invention is to provide an ironing machine in which an automatic cen-

ter-locating device is employed to feed the pieces to the machine in predetermined relative positions and in which a folding device is employed to automatically fold such pieces upon the centers so located.

Other objects and advantages will be apparent from a study of the following specifications read in connection with the accompanying drawings, wherein

Figure 1 is a side elevational view of an ironing machine constructed in accordance with our invention;

Fig. 2 is a side elevational view of an ironing machine shown in Fig. 1, as viewed from the opposite side thereof;

Fig. 3 is a vertical sectional view of the machine shown in Figs. 1 and 2, the section being taken along line III—III of Fig. 4;

Fig. 4 is a vertical sectional view, taken along line IV—IV of Fig. 3;

Fig. 5 is a detail, sectional view, taken along line V—V of Fig. 3;

Fig. 6 is a detail, sectional view, taken along line VI—VI of Fig. 3;

Fig. 7 is a detail, sectional view, taken along line VII—VII of Fig. 3;

Fig. 8 is a detail, plan view of the center-finding and feeding device shown in Figs. 1, 2 and 3;

Fig. 9 is a detail view of a set of links employed with the center-locating device shown in Fig. 8;

Fig. 10 is a detail view of the gripping or holding device employed with the center-locating device shown in Fig. 8;

Fig. 11 is a detail view illustrating the manner of fastening ironing pads to our ironing device;

Fig. 12 is a detail, sectional view, taken along line XII—XII of Fig. 11; and

Fig. 13 is a detail, perspective view of a rotor assembly employed with our ironing device.

Referring to the drawings, we have illustrated our ironing and folding machine as comprising a suitable frame formed of two side plates 1 and 2, the tops of which are interconnected by means of a suitable top plate 3 while the bottoms of the side plates 1 and 2 are connected together by suitable spacer bolts 4 and 5 to comprise a relatively rigid frame within which and upon which the operative mechanism of our ironer may be assembled.

By referring particularly to Figs. 3 and 4, it will be observed that the interior surfaces of the side plates 1 and 2 are cut away, as indicated at 6 and 7, to form a pair of internal bearing mem-

bers upon which may be mounted a rotor assembly 8. The rotor assembly 8 is illustrated particularly in Fig. 13 as comprising an end spider 9, the circular exterior surface of which conforms 5 with the interior surface of the groove 6 on the side plate 1, the spider 9 being formed with an outwardly extending boss 10 journaled in a suitable opening 11 in the side plate 1, preferably at the center of the side plate 1.

10 The opposite end of the rotor assembly 8 is formed of an annular ring 12, the exterior surface of which conforms with the interior surface of the groove 7 in the plate 2 and forms therewith the sole bearing surface between the left-hand end 15 of the spider assembly 9 and the side plate 2 (as viewed in Fig. 4). The ring 12 is interconnected with the spider 9 to form a unitary assembly by means of a plurality of cross rods 13, in the form of the device shown herein there being six cross rods 13, evenly spaced about the periphery of the ring 12.

15 The rotor assembly 8 is preferably employed to form the ironing surface upon which the napkins, handkerchiefs, or other flat work pieces, may be placed, during the initial ironing operations, and for this purpose we have illustrated the rotor assembly as being provided with a plurality of supporting plates 14, each of which is formed of a flat metal plate bent at its center on an angle of 20 approximately 120° so that when the plates are assembled upon the rotor 8 with one of the cross rods 13 at the bend of each of the plates, the set of six plates form a substantially hexagonal surface surrounding the rotor assembly.

25 It will be observed from an inspection of Fig. 3 that the construction and mounting of the plates 14 is such that each of the flat surfaces of the hexagon is formed by one-half of the area of one plate and by one-half of the area of its adjacent 30 plate the two ends of the adjacent plates being spaced apart as indicated at 15 at a point exactly at the center of the flat surface of the hexagon.

35 We prefer to provide the ironing surface of the rotor 8 with a suitable padding or resilient cloth covering to contact the articles to be ironed during the ironing operation, and for this purpose we have illustrated each of the plates 14 as being covered with a sheet 16 of suitable cloth material, such as flannel, or similar material, having a relatively thick pile or nap. Each of the sheets 16 is preferably secured to its associated plate 14, as illustrated particularly in Figs. 3, 11 and 13, as by turning the front and rear edges thereof back beneath the plate 14, as is illustrated particularly 40 in Fig. 11 at 17. The inturned edge of the sheet 16 may be held in place by any suitable securing device, though we prefer to provide a clamping plate 18 for each edge of the sheet 16 secured thereto in any suitable manner. As is particularly 45 illustrated in Figs. 3, 11 and 12, the edges of the plates 14 may be suitably supported upon the spider 9 and the ring 12, as by providing upturned ears 19 on the plates 14 adapted to receive screws 20 threaded into the side walls of the ring and spider, the screws 20 being also employed for the 50 purpose of securing the clamping plates 18 in place in proper associated relation with the plates 14.

55 The application of heat and pressure to the articles to be ironed may be accomplished in any suitable manner, though we prefer to employ an ironer 21 comprising essentially, a relatively heavy block of suitable material, such as metal, having an area approximately equal to one of the 60 hexagonal surfaces of the rotor 8. The ironer 75

21 is preferably mounted at the top of the frame formed by the plates 1 and 2 so that the ironer may be urged into pressing relation with the articles to be ironed under the influence of gravity.

65 The side plates 1 and 2 are each provided with an upstanding extension 22 across which the top plate 3 is secured to form a mounting for the ironer 21, permitting the same to be reciprocated vertically relative to the rotor 8. The ironer 21 70 may be mounted and operated in any suitable manner. For the purpose of illustrating the same, it is shown herein as being secured to the lower end of a piston rod 23, the upper end of which bears a piston 24 operating in a steam or other fluid pressure cylinder 25 so that upon admission of steam or other fluid pressure into the cylinder 25 the ironer 21 will be lifted to such position as will permit the rotor 8 to rotate without contact with the ironer, and when pressure is released from the cylinder 25 the ironer will descend by gravity to apply pressure to the articles supported upon the rotor.

75 The ironer 21 may be heated in any suitable manner, as by forming the same of hollow construction, permitting the admission of steam thereto, or by providing the same with any suitable, well-known electric heating arrangement familiar to those skilled in the art.

80 In the form of the device illustrated herein, employing a hexagonal surface on the rotor, it will be observed that a succession of napkins or other pieces may be placed one at a time upon each of the surfaces of the rotor 8 and brought into position immediately below the ironer 21 by intermittently moving the rotor through one-sixth of a revolution at a time, and for this purpose we have illustrated driving means for the rotor 8 as comprising a star-wheel 26 keyed as at 27 to the extending boss 10 of the spider 9, the star-wheel being provided with six teeth 28 spaced evenly around the wheel. A pin drive is employed for intermittently engaging the star-wheel, such pin drive comprising a drive pin 29 secured upon a crank arm 30 which is in turn rigidly secured to a shaft 31 extending through both of the side plates 1 and 2 of the machine and having secured upon the left-hand end thereof, as viewed in Fig. 4, a suitable drive gear 32, or any other suitable device to which motive power from a suitable prime mover source may be applied.

85 The shaft 31 is arranged to be continuously rotated by its prime mover during the entire operation of the machine, while the pin 29 is arranged to engage the teeth of the star-wheel 26 only once in each revolution of the shaft 31, as by providing a suitable cam 33 secured to the exterior of the side plate 1 so shaped and located as to engage the outer end of the pin 29 when the crankarm is rotated to a position to bring the pin 29 to a position substantially immediately above the shaft 31.

90 By referring particularly to Fig. 4, it will be observed that the cam 33 is bent outwardly, as indicated at 34, to provide an inwardly sloping cam surface 35 engageable by the pin 29 to move the pin toward the star-wheel, the pin 29 being provided with a suitable compression spring 36 normally holding the pin out of possible engagement with the star-wheel. Thus each time the shaft 31 is moved through one revolution in the direction indicated by the arrow on Fig. 2, the pin 29 will engage the star-wheel and move the star-wheel one-sixth of a revolution before the pin 29 is released by the cam 33, and thereafter continued movement of the shaft 31 through the 75

remainder of its revolution will not be accompanied by further movement of the star-wheel and its rotor 8.

From an inspection of Figs. 1 and 4, it will be observed that the left-hand ends of the shaft 31, as viewed in Fig. 4, may be provided with a suitable operating mechanism for causing movement of the ironer 21 in proper timed relation with the rotation of the rotor 8, as by providing a cam 37 upon the shaft 31 to engage an operating rod 38 associated with a control valve 39 for controlling the admission of fluid pressure to the ironer operating cylinder 25. By selecting the shape and the position of mounting of the cam 37 upon its shaft 31, the ironer 21 may be lifted just prior to the engagement of the pin 29 and its star-wheel so that the ironer 21 will be lifted out of the way of the moving rotor just prior to the movement of the rotor and the ironer will be permitted to descend to the new surface of the rotor as soon as the pin 29 is released from the star-wheel at the completion of the forward movement of the rotor 8.

With the apparatus thus far described, napkins, handkerchiefs, or other flat pieces placed one at a time upon each of the flat surfaces of the rotor 8 may be automatically moved into ironing position beneath the ironer by the successive rotation of the rotor 8, and it will be observed that if each of these pieces is so placed upon its surface of the rotor that the space 15 lies immediately beneath the center of the napkin, such napkin may be folded at the space 15 to fold the napkin properly upon its center.

To properly space and locate the napkin upon its ironing surface, we prefer to provide a feeding mechanism to automatically center the napkin upon the rotor, irrespective of the size or varying dimensions of successive pieces to be handled by the machine.

In Figs. 1, 2, 3 and 8, we have illustrated such feeding mechanism at 40 as comprising a backing plate 41 mounted upon a bracket 42 which is in turn pivoted upon a shaft 43 extending between and journaled in the side plates 1 and 2 and as having outwardly extending ears 44 formed thereon. On the upper surface of the backing plate 41 we provide four U-shaped brackets 45, 46, 47 and 48. The brackets 45 and 46 are arranged in alignment with each other upon the right-hand side of the plate 41, as viewed in Fig. 8, and constitute a continuous bearing support for a rod 49, while brackets 47 and 48 are similarly located upon the left-hand side of the plate 41 and constitute a support for a second rod 50. The rods 49 and 50 constitute bearing members for the opposite ends of a slide 51 which extends across the plate 41 near the upper end thereof and also constitute bearing members for a similar slide 52 located and extending across the lower end of the plate 41. The slides 51 and 52 are interconnected with each other by means of a pair of cross links 53 and 54 pivotally joined together at their centers as by means of a suitable bolt 55, while the outer ends of the links are provided with slots 56 each engageable with a pin 57 extending rearwardly from the ends of the slides 51 and 52. Thus any movement of the slide 51 toward or away from the center of the plate 41 will be accompanied by an equal and opposite movement of the slide 52 toward and away from the center of the plate 41. Thus if a napkin has its upper edge secured to the plate 51 and the slides are moved toward the center until the lower edge of the napkin abuts a predetermined point on the

slide 52, the napkin will have its horizontal center located at the exact horizontal center of the plate 41. This construction, therefore, constitutes a device for locating the horizontal center of the napkin as it is placed upon the feeding device 40.

By referring particularly to Fig. 8, it will be observed that the bar 51 has attached at its center a bracket 58 which extends as illustrated particularly in Figs. 1 and 2, substantially parallel to the plate 41. The bracket 58 has mounted thereon a shelf 59 upon which the napkin may be spread so that both the napkin and the shelf 59 may be moved upwardly and downwardly to properly center the horizontal center of the napkin 15 with the horizontal center of the plate 41. It will also be observed that the lower bar 52 has a strap 60 attached thereto, extending over the upper surface of the shelf 59 to constitute a guide which the lower edge of a napkin on the shelf 20 59 may abut when the napkin is properly centered upon the shelf.

Slidably mounted upon the bar 51 is a pair of blocks 61 and 62. The block 61 is secured in any suitable manner, as by welding, to a bearing member 63 having flanges 64 and 65 downturned therefrom to engage the side edges of the block 61 so that the bearing 63 with its block 61 may be moved horizontally along the bar 51. The bearing member 63 may be retained upon the bar 30 51 in any suitable manner, as by an elongated strap 66 secured as at 67 and 68 to the bar 51 and passing over the bearing members 63 to prevent them from moving away from the bar 51.

It will be observed that the bar 51 is provided with a pair of elongated slots 69 and 70 through which pins 71 and 72 on the blocks 61 and 62, respectively, may project, the slots 69 and 70 each extending for a considerable distance along the length of the bar 51.

The block 61 is provided with a vertically extending slot 73, in which is located a grip member 74, the same being retained in the slot 73 by means of a spring 75, one end of which passes through the grip 74, while the other end 76 of the spring bears upon the base of a horizontal slot 77 intersecting the slot 73.

Likewise the block 62 is provided with a grip 78 similarly retained by means of a spring 79. The lower ends of the grips 74 and 78 are each 50 provided with a prong 80 and 81, respectively, and these prongs extend to a position substantially in alignment with the forward edge of the block 61 at a point immediately adjacent the upper edge of the shelf 59 so that by depressing 55 the rear ends of the grips 74 and 78 the grips will be rotated relative to the blocks 61 and 62 to raise the prongs out of the slots 73 and permit the upper edge of a napkin to be inserted between the prongs and the blocks 61 and 62.

By referring particularly to Figs. 8 and 9 it will be observed that the block 61 is provided with a link 82 pivoted as at 83 to the bar 51, and having an elongated slot 84 extending longitudinally thereof to engage the lower end of the pin 71. 65 Similarly, the block 62 is provided with a link 85 pivoted as at 86 to the bar 51 and having a similar elongated slot 87 engaging the lower end of the pin 72. The lower end of the link 85 is connected by a bar 88 to a point 89 on the link 82 spaced upwardly from the pivot point 83 of that link so that any movement of the slide 61 along the bar 51 will, through the linkage 82—88—85 be accompanied by a similar but opposite movement of the block 62.

By properly initially locating the blocks 61 and 62 at equal distances on opposite sides of the vertical center of the plate 41, it follows that any movement of the block 61 relative to the center 5 will be accompanied by an equal and opposite movement of the block 62 toward or away from the center. Thus by securing the extreme corners of the upper edge of the napkin to the grips 74 and 78 movement of the blocks 61 and 62 to 10 stretch the napkin flat will automatically locate the vertical center of the napkin in alignment with the vertical center of the plate 41. If desired, the links 82 and 85 may be normally urged outwardly (that is to a napkin-stretching position) by means of a spring 90 connected respectively to the link 82 and the bar 88.

With the construction of the napkin-feeding device thus far described, it will be apparent that all that an operator has to do is to grasp a corner of the upper edge of a napkin, place the same upon the shelf 59 and engage the grips 74 and 78 with the corners of the napkin, which operation will automatically find the vertical center of the napkin and locate the same upon the vertical center of the plate 41. Then by drawing the bar 51 bodily upwardly or downwardly until the lower edge of the napkin abuts the guide strap 69 of the bar 52, the napkin will have its horizontal center also properly located relative to the horizontal center of the plate 41.

The napkin so located upon the feeding device 40 is now ready to be placed upon one of the ironing surfaces of the rotor 8. This may be accomplished by rotating the entire feeding mechanism 40 about its shaft 43, as illustrated particularly in Fig. 3, to bring the napkin which is now supported upon the shelf 59 into contact with that hexagon surface presented forwardly and upwardly upon the machine. The movement of the feeding mechanism 40 may be accomplished by hand, if desired, though we prefer to move the same automatically, as will be hereinafter described, and we provide an automatic releasing device for releasing the grips 74 and 78 when the napkin is pressed into contact with the padding or covering of the plates 14, which mechanism consists essentially in a pair of rods 91 and 92 extending from opposite ends of the shaft 43 in such position that the outer ends of the rods 91 and 92 will engage a cross rod 93 extending through the outer ends of both grips 74 and 78. The rod 93 is slidably mounted in the bracket 58, as by means of passing the same through an elongated slot 95 in the bracket, and securing the same against lateral movement by means of a pair of collars 96, one on each side of the bracket 94 mounted upon the bar 51. Thus as the napkin is pressed tightly upon the cloth covering of the plates 14 the grip members will be operated to release their grip upon the napkin and the napkin will then be secured upon the cloth covering of the plates by the adhesive action of the pile of the cloth covering.

While the transfer of the napkin from the feeding mechanism 40 may be accomplished manually, we prefer to automatically move the transfer mechanism toward the rotor and transfer the napkin therefrom at a predetermined time relative to the successive movements of the rotor, 70 and for this purpose we have illustrated an automatic feeding device for operating the feeding mechanism 40 as consisting of a lever 97 pivoted to the outside of the frame side plate 1, as indicated at 98, in such position as to be engaged 75 by a cam surface 99 formed on the outer ex-

tremity of the crankarm 30 to be swung to the right as viewed in Fig. 2 upon each rotation of the shaft 31. The lever 97 is connected by a crank 100 to an ear 101 on the bracket 42 so that as viewed in Fig. 2 movement of the lever 97 will cause the bracket 42 to swing the feeding mechanism 40 about its pivot 43 from the position shown in Fig. 2 to the position shown in dotted lines in Fig. 3.

The shaft 43 is likewise arranged to be given 10 an oscillatory motion by the cam surface 99, as by connecting the shaft 43 rigidly to a short lever 102 which is in turn connected by the link 103 to a second link 104 pivoted, as at 105, to the lever 97, the link 104 being arranged to also be engaged 15 by the cam surface 99 as the crank 30 is rotated so that after the feeding mechanism 40 has pressed the napkin into contact with the rotor 8 it will swing the rods 91 and 92 outwardly with respect to the machine to automatically 20 press the rod 93, releasing the grips 74 and 78 from the napkins. The rods 91 and 92 will be held in their grip-releasing position until the feeding mechanism 40 has started its return movement to the position shown in solid lines in 25 Fig. 2. The return movement of the feeding mechanism 40 may be assisted by a coil spring 106, while the outermost limit of movement of the feeding mechanism 40 may be determined by a suitable stop 107 secured to the side 1 of the 30 frame of the machine.

With the apparatus thus far described it will be apparent that a napkin placed upon the feeding mechanism 40 and moved into position upon the ironing surface plates 14 will be ready to be 35 ironed by the ironer 21 at the next movement of the rotor 8. It will also be observed that the napkin, irrespective of its size, will be located upon the ironing surface with both its vertical and its horizontal centers located along predetermined 40 lines on the ironing surfaces.

After the ironing of the napkin takes place by the ironer 21, the next successive movement of the rotor 8 will bring the napkin to the position shown at 108, at which time the napkin has been pressed 45 out flat and is ready now to be folded along one of its centers.

Since the napkin has been placed upon its ironing surface with its horizontal center accurately aligned with a predetermined horizontal 50 line on the ironing surface, the napkin may readily be folded automatically along its horizontal center by pressure applied at the space 15 between the plates 14 forming the particular ironing surface upon which the napkin is located. This folding 55 may be readily accomplished by a tucking member 109 comprising a relatively thin flat plate slidably mounted in a suitable guide 110 arranged substantially radially relative to the center about which the rotor 8 rotates. We have illustrated 60 the plate 109 and its guide 110 as mounted upon a pair of brackets 111, each of which is mounted upon a block 112 rigidly secured to a spacer bar 113 extending between the plates 1 and 2 of the frame of the machine. The blocks 112 also constitute 65 mounting members for a shaft 114, the outer end of which is provided with a crankarm 115 extending below the shaft 114 to be engaged by the outer end of a rockpin 116 slidably mounted in a guide bearing 117, the opposite end 118 of 70 the pin being engaged by the cam surface 99 as the shaft 31 is rotated. The shaft 114 has rigidly secured thereto a rod 119 which extends, as shown in Fig. 3, through a slot 120 in the tucking plate 109 so that upon each movement of the crank 115 75

by its pin 166 the rod 119 will be moved to the right, as viewed in Fig. 3, to drive the tucker plate 109 into the space 15 between adjacent ironing surface plates 14, and thus tuck the horizontal center of the napkin through the space 15 into engagement with folding and ironing rollers 121 and 122 to form and iron the initial fold of the napkin.

If desired, friction between the rod 119 and the plate 109 may be reduced by mounting a plate 123 upon the tucker plate 109 and securing thereto a suitable roller 124 against which the rod 119 may bear.

By referring particularly to Fig. 5, it will be observed that the roller 121 is formed of a pair of sections *a* and *b*, each rigidly secured to a shaft 125 but with a space 126 therebetween, and similarly the roller 122 is formed in half sections *c* and *d* spaced and mounted upon a shaft 127. The folding and ironing rollers 121 and 122 are arranged to be power driven to draw the napkin between them, while heat may be supplied to the rollers 121 and 122 in any suitable manner, as will be understood by those skilled in the art. For example, either the rollers may be provided with suitable electric heating coils or the shafts 125 and 127 may be formed of hollow construction permitting the supplying of steam to the interior of the rollers. As the napkin feeds through the rollers 121 and 122, we have arranged to have the same pass onto the receiving table formed of a pair of shelves 128 and 129, illustrated more particularly in Figs. 3, 4 and 7, and arranged to be secured as by means of screws 130 to a downwardly extending bracket 131 which is in turn supported upon a shelf 132 secured to the side plate 2.

It will be observed from an inspection of Figs. 4 and 7 that the two shelves 128 and 129 are separated by a space 133 along a plane aligned with the vertical center of the napkin when properly placed upon the ironing surfaces of the rotor 8. Thus the napkin which has been initially folded may now be passed down through the space 133 into engagement with a pair of secondary rollers 134 and 135 to again fold and iron the napkin upon the vertical center thereof. The feeding of the napkin down into engagement with the rollers 134 and 135 may be accompanied by a secondary tucker plate 136 mounted between a pair of upstanding brackets 137 supported upon the shelf 132. The secondary tucker plate 136 is illustrated as having a roller 138 secured thereto to be engaged by the bifurcated end 139 of a lever 140 which is in turn secured to a shaft 141 extending through the side plate 2 of the frame of the machine.

By referring particularly to Fig. 1, it will be observed that the shaft 141 has a crank 142 secured thereto, the upper end of which forms a pawl 143 engageable by a notch 144 in the end of a link 145 secured to and movable with the feeding mechanism 40, as indicated at 146. Thus each time the feeding mechanism 40 is moved inwardly to place a new napkin upon the ironing surfaces, the tucker plate 136 will be moved downwardly to press that napkin which has just been ironed by the rollers 121 and 122 into engagement with the refolding rollers 134 and 135.

Again the rollers 134 and 135 may be supplied with heat in any suitable manner, as described with reference to the rollers 121 and 122.

The coordination of the operations of the rotation of the rotor, the operation of the feeding mechanism 40, the operation of the initial tucker

109, and the operation of the secondary tucker 136 as hereinbefore described, includes the drive mechanism through which power for all of these operations is transmitted through the shaft 31 and crankarm 30 so that by properly gearing the shaft 31 to the rollers 121-122 and rollers 134-135, all of the power operations of the machine may be accomplished by supplying rotary power to the single shaft 31.

By referring particularly to Figs. 1, 3 and 6, it will be observed that power for operating the rollers 134 and 135 may be transmitted from the shaft 31 by means of a spur gear 147 coupled through idler gears 148 to a pinion 149 on the end of a stub shaft 150. The stub shaft 150 extends 15 through the side plate 2 of the frame of the machine and bears upon its inner end a miter-gear 151 engaged with a second miter-gear 152 secured to a jackshaft 153 mounted in suitable bearings 154, 155 in a bracket 156 secured upon 20 the underneath surface of the shelf 132. The inner end of the shaft 153 bears a spur gear 157 connected through an idler gear 158 with a pinion 159 rigidly secured to the shaft 160 of the roller 134. 25

By referring particularly to Fig. 7, it will be observed that the shaft 160 is rotatably mounted in the bracket 131 and bears a second pinion 161 which is connected through idlers 162 and 163 to the pinion 164 mounted rigidly upon the shaft 30 165 of the roller 135. Since the napkins or other flat pieces which are to be ironed by the machine will vary considerably in thickness, it is necessary to provide some slight play between the rollers 134 and 135, and for this purpose we have 35 illustrated the shaft 165 of the roller 135 as being movably mounted in the bracket 131. This is illustrated herein as comprising an elongated arcuate slot 166 formed in the bracket 131, the center of curvature of which coincides with the 40 center of rotation of the shaft 167 upon which the idler 163 is mounted, the width of the slot 166 being equal to the diameter of the shaft 165 so that a napkin of unusual thickness may press the roller 135 away from the roller 134 without 45 unmoving the gears 163 and 164.

The opposite ends of the shafts 160-165 are likewise mounted in a bracket 168, the shaft 160 being fixedly rotatable in the bracket 168 while the shaft 165 is mounted in an arcuate slot 169 50 so that this end of the shaft 165 may also move to accommodate varying thicknesses of material.

Both ends of the shaft 165 are normally urged toward the shaft 160 by means of suitable springs 170, each of these springs being connected to a 55 suitable rider 171 mounted loosely upon the shafts.

It may also be understood that a similar mounting of the shafts 125 and 127 for the rollers 121 and 122, respectively, may be provided to permit 60 these rollers also to separate a greater distance for varying thicknesses of material. This mounting includes the journaling of the shafts 125 and 127 in bearing brackets 172 and 173, the shaft 127 extending also through the side plate 65 2 of the frame of the machine and has a pinion 174 connected through idlers 175 and 176 to the gear 147 on the shaft 31.

The shaft 127 also bears a pinion 177 connected through an idler 178 to a pinion 179 on the 70 shaft 125, the location and connection of the pinions 177-178-179 being identical with that described with reference to the pinions 161-162-163-164 for the rollers 134 and 135.

It will, therefore, be observed that we have pro- 75

vided an ironing machine in which napkins may be fed into the machine in proper centering relation relative to the ironing surfaces upon which they are to be ironed and which will, therefore, 5 permit the accurate folding of the napkins along such centers as the napkin progresses through the machine by successive movements of the rotor 8.

It will also be observed that the napkins may 10 be fed to the machine by employing the feeding mechanism 40 automatically finding the centers of varying sizes of napkins and properly locating the napkins upon the ironing surfaces of the rotor.

15 It will also be observed that with our machine the folding of the napkin is not only accomplished but that the napkin is ironed upon the fold so that a napkin fed into our machine is first ironed flat, then folded upon one center 20 and ironed, then folded upon another center and ironed, and the napkin is thus completely finished ready for use. While the finished napkin may be passed out of our machine by any suitable means, we have diagrammatically illustrated 25 herein a transporting mechanism which will receive the napkin from the rollers 134 and 135 and pass the same outwardly through an exit opening 180 as they are finished. The transporting mechanism illustrated herein consists essentially of an endless belt conveyor 181 mounted 30 to operate upon suitable rollers, the inner end 182 of which is illustrated as being mounted substantially below the space between the rollers 134 and 135. The conveyor may be driven by any suitable means so long as the movement of 35 the conveyor belt is sufficiently rapid to receive the downcoming end or edge of the napkin and move the same toward the exit opening at a speed preventing the napkins from piling up immediately beneath the rollers.

40 While the feeding mechanism illustrated herein moves the rotor only through 60° of movement for each rotation of the shaft 31, it may be desirable to provide a folding mechanism for 45 preventing inadvertent movement of the rotor during the ironing operation or during any of the other operations of machine, and for this purpose we have illustrated a folding device as comprising a lever 183 pivoted to the slide bearing 117, as indicated at 184, the lever 183 being 50 provided upon its lower edge with a notch 185 engageable with one of the teeth 28 of the star-wheel so that when so engaged the star-wheel cannot be moved. The outer end 186 of the lever 55 183 may be projected into the path of movement of the cam surface 99 of the crank 30 so that immediately prior to the initial movement of the pin 29 to engage the star-wheel the lever 183 will be momentarily lifted to release the star-wheel 60 while as soon as the forward movement of the rotor is completed the lever 183 will again engage its notch upon the ends of the teeth of the star-wheel to hold the same against further movement until the next forward movement of 65 the rotor.

70 While we have shown and described the preferred embodiment of our invention, we do not wish to be limited to any of the details of construction shown herein, except as defined in the appended claims.

We claim:

1. In an ironing device for flat work pieces, means forming a supporting surface upon which a work piece to be ironed may be placed, and 75 means for feeding flat work pieces to said sup-

porting surface with transverse center lines of said work pieces aligned with predetermined transverse center lines of said supporting surface.

2. In an ironing device for flat work pieces of varying dimensions, means forming a supporting surface upon which flat work pieces may be placed flat ready for ironing, having dimensions in excess of the maximum dimensions of the work pieces to be ironed thereon, and means for feeding flat work pieces of varying dimensions to said supporting surface with transverse center lines of said work pieces aligned with transverse center lines of said supporting pieces, whereby said work pieces will be accurately and centrally located upon said supporting surface irrespective of their dimensions.

3. In an ironing device for flat work pieces of varying dimensions, means forming a supporting surface upon which flat work pieces may be placed flat ready for ironing, having dimensions in excess of the maximum dimensions of the work pieces to be ironed thereon, and means for feeding flat work pieces of varying dimensions to said supporting surface with transverse center 25 lines of said work pieces aligned with transverse center lines of said supporting surface, and means operating along the center line of said supporting surface for engaging the center line of work pieces thereon to fold the same. 30

4. In an ironing device for flat work pieces, a frame, a rotor mounted for rotation in said frame and having a plurality of work piece supporting surfaces distributed therearound, means for feeding work pieces to said surfaces as the 35 surfaces are successively presented to a predetermined position by rotation of said rotor, and ironing means for successively ironing pieces on surfaces presented to a succeeding position.

5. In an ironing device for flat work pieces, a 40 frame, a rotor mounted for rotation in said frame and having a plurality of work piece supporting surfaces distributed therearound, means for feeding work pieces to said surfaces as the 45 surfaces are successively presented to a predetermined position by rotation of said rotor, ironing means for successively ironing pieces on surfaces presented to a succeeding position, and means for moving said rotor, said feeding means and said ironing means in predetermined timed 50 relation to each other.

6. In an ironing device for flat work pieces, a frame, a rotor mounted for rotation in said frame and having a plurality of work piece supporting surfaces distributed therearound, means for feeding work pieces to said surfaces as the 55 surfaces are successively presented to a predetermined position by rotation of said rotor, ironing means for successively ironing pieces on surfaces presented to a succeeding position, and means for folding work pieces on said surfaces when moved to a still further successive position by rotation of said rotor.

7. In an ironing device for flat work pieces, a supporting surface upon which work pieces may 65 be supported while flat, having a slot in said supporting surface extending transversely of a work piece thereon, means for folding a work piece including a tucker insertable through said slot to engage a work piece and pass the same 70 through said slot, and ironing means mounted below said surface for receiving said folded work piece and for ironing said folded piece.

8. In an ironing device for flat work pieces, a supporting surface upon which work pieces may 75

- be supported while flat and having a slot in said supporting surface extending transversely of a work piece thereon, a pair of cooperative ironing rollers mounted below said supporting surface with the space between said rollers aligned with said slot, and means for folding a work piece including a tucker insertable through said slot to engage a work piece thereon and pass the same through said slot and into the space between said ironing rollers.
9. In an ironing device for flat work pieces, means for supporting flat work pieces while flat, including a rotor having thereon a plurality of surfaces for receiving work pieces, each of said surfaces being provided with a slot extending transversely of work pieces placed thereon, tucker means for engaging and folding work pieces, means for moving said tucker into and out of the slot in said rotor, means for intermittently rotating said rotor, and for moving said tucker only when said tucker is aligned with one of said slots.
10. In a positioning device for flat work pieces, a supporting shelf upon which pieces may be placed, means at one edge of said shelf for engaging the ends of one edge of a work piece, means mounting said engaging means for equal and opposite movement relative to a line drawn through the center of said shelf whereby a work piece so engaged will have its center line accurately aligned with the center line of said shelf.
11. In a positioning device for flat work pieces, a supporting shelf upon which pieces may be placed, means at one edge of said shelf for engaging the ends of one edge of a work piece, means mounting said engaging means for equal and opposite movement relative to a line drawn through the center of said shelf, whereby a work piece so engaged will have its center line accurately aligned with the center line of said shelf, a guide for the opposite edge of said work piece, means mounting said guide and said engaging means for equal and opposite movement relative to the transverse center line of said shelf, whereby alignment of the opposite edge of said work piece in said guide will accurately align the transverse center of said work with said transverse center line of said shelf.
12. In an ironing device for flat work pieces of varying dimensions, means forming a supporting surface upon which flat work pieces may be placed flat ready for ironing, having dimensions in excess of the maximum dimensions of the work pieces to be ironed thereon, and means for feeding flat work pieces of varying dimensions to said supporting surface with transverse center lines of said work pieces aligned with transverse center lines of said supporting surface, folding means operable along a plane extending through one of the center lines of said supporting surface for folding said work piece along one of its center lines, and a second folding means operable along a plane extending through the other of the center lines of said supporting surface to engage said folded work piece and refold the same along the other of its center lines.
13. In a device for folding rectangular work pieces, means forming a supporting surface for
- receiving said work pieces while flat, means for feeding said work pieces to said supporting surface with transverse center lines of said work pieces aligned with transverse center lines of said supporting surface, folding means operable along a plane extending through one of the center lines of said supporting surface for engaging and folding said work piece along one of its center lines, a second supporting surface for receiving said folded work piece, and a second folding means operable along a plane extending through the other of said center lines of said supporting surface for engaging said folded work piece and folding the same along the other of its centers.
14. In a device for folding rectangular flat work pieces, means forming a supporting surface for receiving and holding pieces while flat and having a slot extending therethrough along one of the center lines of said supporting surface, means for feeding said work pieces to said supporting surface with transverse center lines of said work pieces aligned with the two transverse center lines of said supporting surface, means for folding said work piece along one of its center lines including a tucker insertable through said slot to fold said work piece and pass the same through said supporting surface, a pair of cooperating folding rollers mounted below said supporting surface and aligned with said slot for rolling said folded work piece therebetween, a second supporting table adjacent said rollers for receiving said folded work piece therefrom, and having a slot extending in a plane coincident with the transverse center line of said supporting surface, a second tucker movable through said slot in said second supporting surface to fold said work piece along the transverse center line thereof.
15. In a device for folding rectangular flat work pieces, means forming a supporting surface for receiving and holding pieces while flat and having a slot extending therethrough along one of the center lines of said supporting surface, means for feeding said work pieces to said supporting surface with transverse center lines of said work pieces aligned with the two transverse center lines of said supporting surface, means for folding said work piece along one of its center lines including a tucker insertable through said slot to fold said work piece and pass the same through said supporting surface, a pair of cooperating folding rollers mounted below said supporting surface and aligned with said slot for rolling said folded work piece therebetween, a second supporting table adjacent said rollers for receiving said folded work piece therefrom, and having a slot extending in a plane coincident with the transverse center line of said supporting surface, a second tucker movable through said slot in said second supporting surface to fold said work piece along the transverse center line thereof.
16. In a device for folding rectangular flat work pieces, means forming a supporting surface for receiving and holding pieces while flat and having a slot extending therethrough along one of the center lines of said supporting surface, means for feeding said work pieces to said supporting surface with transverse center lines of said work pieces aligned with the two transverse center lines of said supporting surface, means for folding said work piece along one of its center lines including a tucker insertable through said slot to fold said work piece and pass the same through said supporting surface, a pair of cooperating folding rollers mounted below said supporting surface and aligned with said slot for rolling said folded work piece therebetween, a second supporting table adjacent said rollers for receiving said folded work piece therefrom, and having a slot extending in a plane coincident with the transverse center line of said supporting surface, a second tucker movable through said slot in said second supporting surface to fold said work piece along the transverse center line thereof, and a second set of cooperating rollers mounted below said second supporting surface and aligned with the slot therein for receiving and rolling said work piece after the second fold has been made therein.
